BAKER'S OVEN

Charles T. Hatch, Albion, Mich., assignor to
Union Steel Products Company, Albion, Mich.

Application November 2, 1934, Serial No. 751,114

25 Claims. (Cl. 107—59)

This invention relates to bakers' ovens of the type employing a reel or conveyor having a series of suspended shelves for carrying the goods in the oven, the shelves being maintained in equilibrium mainly by gravity.

Heretofore, in bakers' ovens of this character, there is present the possibility of damage to the load or to the oven in the event of the load not being properly placed upon the shelves and jamming between the shelves and walls and load or between the shelves and/or load as they pass each other at the top and bottom of the conveyor. It is possible for a serious accident to occur in the event that the operator does not place the pans properly upon the shelves or properly load the shelves. I have observed that whenever this has occurred it has been almost impossible to definitely fix the responsibility due to the fact that the accident itself destroyed all evidence as to exactly what caused it.

The main object of my invention is to provide automatic means in a baker's oven of this character for minimizing the possibility of an accident of this nature due to the pans jamming between the shelves or between the oven parts and the shelves.

Another object of my invention is to provide a conveyor having its shelves stabilized sufficiently to enable the baker to load them without undue swaying of the shelves and yet at the same time they are free enough so that no undue friction is set up which would cause an excessive vibration in operation.

A further object is to provide means for preventing the operation of the conveyor unless the control means is in operative condition.

Objects relating to details and economies of my invention will appear from the description to follow. The invention is defined and pointed out in the claims.

A structure which is a preferred embodiment of my invention is illustrated in the accompanying drawings, in which:

Fig. 1 is a fragmentary view in front elevation of a baker's oven embodying the features of my invention.

Fig. 2 is an enlarged transverse vertical section on a line corresponding to line 2—2 of Fig. 1.

Fig. 3 is an enlarged fragmentary perspective view of the conveyor.

Fig. 4 is an enlarged fragmentary detail section on a line corresponding to line 4—4 of Fig. 2.

Fig. 5 is a fragmentary end elevation of the conveyor, the dotted lines showing how the several shelves tilt in unison.

Fig. 6 is a simplified diagrammatic representation of the control means.

In the embodiment of my invention illustrated in the drawings, numeral 1 in general indicates a baker's oven having a substantially circular casing 2 provided with vertical end walls 3, 3. The casing is heat insulated as shown by Fig. 2 and is provided with a longitudinal door opening 4 having a pair of longitudinally aligned doors 5, 5 hinged to the rod 6 at the bottom of the door opening. A gas burner 7 is arranged in the bottom 8 of the oven, there being a flame deflecting plate 9 mounted above the burner.

The ends of the conveyor shaft 10 are journaled upon the end walls 3, 3, the shaft being driven by the conveyor driving motor 11 through suitable gears. The end frames or annular spiders 12 of the conveyor are fixed to the shaft 10 in spaced relation for rotation therewith and are provided with radial supports or brackets 13 for the pan shelves 14. The shelves are provided with hangers at their ends pivotally swung between the supports 13 so that they are maintained by gravity in a substantially horizontal position throughout their travel with the rotary conveyor.

The journals 15 of the shelves at one end of the conveyor have depending arms 16 connected thereto and adapted to tilt or swing with the shelves. The lower or outer ends of the arms 16 are connected by means of a series of links 17, the ends of the links being connected to the arms by lateral pivot pins 18 each having an enlarged contact head 19—see Fig. 4. The arm or lever link assembly of the shelves is such that when one shelf is tilted the other shelves are tilted correspondingly as illustrated by Fig. 5. However, the shelves are stabilized sufficiently by this assembly to enable the baker to load them without undue swaying of the shelves and yet at the same time they are free enough so that no undue friction is set up which would cause an excessive vibration when the oven is in operation.

On the inner side of one of the end walls of the casing, I mount a pair of curved resilient contact strips or bars 20 and 21 at opposite sides of the normal path of the heads 19 and normally spaced therefrom to provide therewith a normally open control switch, the strips being positioned adjacent the door opening 4 and extending above and below the same as shown by Fig. 2. The contact strips or contact bars 20 and 21 are preferably made of chromium plated spring steel and are supported only at their ends by means of sup-

ports 22, the ends being bent outwardly as shown and insulated from the end wall of the casing. The contact heads 19 are adapted to project and travel between the contact bars 20 and 21 and permit a predetermined inclination of the shelves before they contact either strip. However, if the shelves should incline more than the predetermined amount, preferably approximately 10° in either direction from the horizontal, the heads will 10 strike one or the other of the contact bars. When this occurs, an electric contact is made which interrupts the control circuit operating the conveyor driving motor 11 and other apparatus to shut down the operation of the oven. This shut-down 15 occurs before any damage has been done either to the material being baked or to the oven itself.

The fact that the shelves are caused to swing in unison makes it possible for me to use comparatively short contact bars or strips, it being 20 only necessary to make these bars long enough to insure at least one shelf being between the bars at all times. Consequently, regardless of the position in the oven at which the obstruction may occur, the effect is transmitted to the shelf whose 25 equalizer pin head is between the contact bars, and as soon as the angle of inclination is 10° either one way or the other from the horizontal, contact is made and the operation of the oven immediately stopped.

30 The drive between the motor 11 and the conveyor shaft 10 is provided with a friction clutch (not shown) which is very easily disengaged by pulling the shaft 23 on which the hand crank 24 is located out toward the front of the oven to 35 engage the hand driving gears (not shown). A few revolutions of the hand crank will back up the conveyor sufficiently to release the pans which have become caught so that the baker can push them back into their proper position on the shelf 40 by means of a stick or peel, thus enabling him to get the oven back into its normal operation within a very short time after the stoppage has occurred.

By reference to Fig. 6, it will be observed that 45 the contact heads 19 are connected to ground 25. The manually operated switch 26 is arranged in the supply circuit 27 in advance of the transformer 28, the secondary of which supplies the control circuit with current at substantially 24 volts. The coil winding 29 of the relay 30 is connected to the control circuit in such manner that when the manually operated switch 26 is closed, the relay is closed and the control circuit is put in operative condition. The double acting relay 50 31 is connected to the control circuit so as to be controlled by the control switch consisting of the contact heads 19 and contact strips 20 and 21, the arrangement being such that when the control switch is closed the coil winding 32 or 55 the relay 31 is energized to open the circuit including the relay winding 33 of the conveyor driving motor switch 34, and at the same time establish the circuit to the bell 35 or other alarm. A holding circuit is also established through the 60 winding 33 to keep the bell ringing until the trouble is corrected. The coil windings 36 and 37 of the blower driving motor switch 38 and gas valve 39 are arranged in series circuit relation with the circuit including the relay winding 65 33 and the normally closed manually opened stop switch 40.

The blower motor 41 is connected to the supply circuit 27 so that under normal conditions it operates when the manually closed switch 26 and 70 the relay 38 are closed. The blower motor 41

operates a blower 42 in conjunction with the gas supply for delivering a proper mixture of gas and air to the burner 7. The starting switch 43 for the conveyor driving motor 11 is connected to the relay coil 33 so as to energize the latter when the switch is momentarily closed. The energization of the coil 33 closes the contacts of the switch 34 and the contacts of the holding switch 44, the latter being in series with the stop switch 40.

Briefly, in operation the manually controlled switch 26 is closed first. This switch must be closed in order to put the oven in operation. On the closing of the switch 26, the relay automatically operates to place the control circuit 31 in operative condition so that when the starting switch 43 is momentarily closed, the coil winding 33 is energized resulting in the operation of the conveyor driving motor 11. The energization of the coil 33 also closes the holding switch 44. The closing of the switch 26 results in the operation 20 of the blower motor 41 and the opening of the gas valve 39.

As long as the contact heads 19 follow their normal path between the contact strips 20 and 21 without touching the latter, the device operates in a normal manner. However, if the shelves should incline more than the predetermined degree from the horizontal, the heads 19 will strike one or the other of the contact strips. When this occurs, the relay 31 is operated, opening the circuit including the coils of relays 34, 36 and 37, thereby stopping the blower motor 41, closing the gas valve 39 and stopping the conveyor driving motor 11. The oven is completely shut down before any damage has been done either to the 35 material being baked or to the oven itself. At the same time that the control circuit is broken, the circuit leading to the electric gong 35 is closed and the bell rings, giving the signal to the operator that something is wrong with the oven. 40 The bell will continue to ring until the manually controlled switch 26 is opened. By investigation, the baker can usually determine just what is causing the difficulty and can back the conveyor up by hand, straighten out the pans which are 45 out of place and start the oven in the usual manner. There are no safety pins to replace nor any electrical equipment to reset. My safety device is automatically placed on guard for the detection of future trouble of the same nature. 50

To make certain that the oven cannot be operated without the safety device being in operation, I provide the relay 30 through which the control circuit current must flow. This relay is actuated by current in the secondary circuit of the transformer 28 which furnishes current to the contact bars inside of the oven. In the event of transformer failure or should the operator forget to throw the line switch 26 supplying the primary current to the transformer, this relay 30 will remain open and it will be impossible to start the oven until electric current is supplied to the contact strips inside of the oven. Consequently, it is impossible to operate the oven without the safety device being on duty to guard against a possible 65 accident.

While I have described my improvements in connection with a baker's oven having a conveyor of the rotary type, it will be appreciated by those skilled in the art that the invention is applicable to ovens having other forms of conveyors such as traveling tray ovens. Traveling tray ovens are very expensive and have a large capacity. It can therefore be appreciated that a simple safety de- 75

vice embodying the features of my invention is extremely desirable on an oven of this type.

In addition to the gong or bell that I use for signaling trouble, other signals such as colored lights can be used with the apparatus.

I have illustrated and described my improvements in an embodiment which I have found very practical. I have not attempted to illustrate or describe other embodiments or adaptations, as it is believed this disclosure will enable those skilled in the art to embody or adapt my improvements as may be desired.

Having thus described my invention, what I claim as new and desire to secure by Letters

15 Patent is:

1. In a baker's oven, the combination of a casing having a door opening at the front, a conveyor having annular end members spaced from the end walls of the casing, a series of longitudinal pan shelves pivotally suspended between said conveyor end members, lever arms connected to the pivots of said shelves at one end of said conveyor, laterally projecting pins on the ends of said arms and having contact heads movable out 25 of their normal path by the tilting of the shelves, links connecting said pins for uniform tilting movement when one shelf is tilted, a pair of curved resilient contact strips mounted on the inner side of one of said end walls at opposite 30 sides of the normal path of said heads and normally spaced therefrom to provide therewith a normally open control switch, the strips being positioned adjacent the door opening and extending above and below the same, and a control circuit including said switch for shutting down the 35 oven when the shelves are tilted sufficiently to cause one of said heads to engage one of said strips and close said switch.

2. In a baker's oven, the combination of a substantially circular casing having vertical end walls and a longitudinal door opening at the front, a rotary conveyor journaled upon said end walls and having end members spaced therefrom, a series of longitudinal shelves pivotally suspended between 40 said end members, lever arms connected to the pivots of said shelves at one end of said conveyor, laterally projecting pins on said arms and having contacts movable out of their normal path by the tilting of the shelves, means connecting said 45 shelves for uniform tilting movement when one shelf is tilted, a pair of curved contact strips mounted on the inner side of one of said end walls at opposite sides of the normal path of said contacts and normally spaced therefrom, the strips being positioned adjacent the door opening and extending above and below the same, and control 50 means for shutting down the oven when the shelves are tilted sufficiently to cause one of said contacts to engage one of said strips.

3. In a baker's oven, the combination of a casing, a conveyor having end members, a series of longitudinal shelves pivotally suspended between said end members, lever arms connected to said shelves at one end of said conveyor, laterally projecting pins on said arms and having contacts movable out of their normal path by the tilting of the shelves, means connecting said shelves for uniform tilting movement when one shelf is tilted, a pair of curved contact strips mounted at opposite sides of the normal path of said contacts and normally spaced therefrom, and control means for shutting down the oven when the shelves are tilted sufficiently to cause one of said contacts to engage one of said strips.

4. The combination with a housing provided

with a door opening at the front thereof, a rotary conveyor within said housing, driving means for said conveyor, an annular series of uniformly spaced shelves pivotally mounted on said conveyor, an arm connected to each shelf so that the swinging movement of the shelf is imparted to the arm, connecting links for the arms whereby the swinging movement of one shelf is imparted to all of them and forces tending to tilt one shelf are resisted by all of them, a control means for said driving means including a contact element carried by each of said arms and traveling in a circular path when the shelves are in normal un-tilted position, and a pair of coacting relatively fixed contact bars disposed in opposed spaced relation on opposite sides of the normal path of the contact elements carried by said arms to be engaged thereby when a shelf is tilted more than a predetermined degree, the fixed contact bars being positioned to be operatively associated with the contact elements of the shelves in operative relation to the door opening and being of a length at least equal to the spacing of the shelves so that there is always a contact bar of one of the shelves in operative relation thereto.

5. The combination with a rotary conveyor, driving means for said conveyor, an annular series of uniformly spaced shelves pivotally mounted on said conveyor, an arm connected to each shelf so that the swinging movement of the shelf is imparted to the arm, connecting links for the arms whereby the swinging movement of one shelf is imparted to all of them and forces tending to tilt one shelf are resisted by all of them, a control means for said driving means including a contact element carried by each of said arms and traveling in a circular path when the shelves are in normal un-tilted position, and a pair of coacting relatively fixed contact bars disposed in opposed spaced relation on opposite sides of the normal path of the contact elements carried by said arms to be engaged thereby when a shelf is tilted more than a predetermined degree.

6. The combination with a housing provided with a door opening at the front thereof, an endless conveyor within said housing, driving means for said conveyor, an annular series of uniformly spaced shelves pivotally mounted on said conveyor, an arm connected to each shelf so that the swinging movement of the shelf is imparted to the arm, connecting links for the arms whereby the swinging movement of one shelf is imparted to all of them, a control means for said driving means including a contact element carried by each of said arms and traveling in a predetermined path when the shelves are in normal position, and a pair of coacting relatively fixed contact bars disposed in opposed spaced relation and on opposite sides of the normal path of the contact elements carried by said arms to be engaged thereby when they depart more than a predetermined degree from their normal path, the fixed contact bars being positioned to be operatively associated with the contact elements of the shelves in operative relation to the door opening and being of a length at least equal to the spacing of the shelves so that there is always a contact bar of one of the shelves in operative relation thereto.

7. The combination with a housing provided with a door opening at the front thereof, an endless conveyor within said housing, driving means for said conveyor, an annular series of uniformly spaced shelves pivotally mounted on said conveyor, an arm connected to each shelf

- so that the swinging movement of the shelf is imparted to the arm, connecting links for the arms whereby the swinging movement of one shelf is imparted to all of them, a control means for said driving means including a contact element carried by each of said arms and traveling in a predetermined path when the shelves are in normal position, and a coacting relatively fixed contact member disposed at the side of the normal path of the contact elements carried by said arms to be engaged thereby when they depart more than a predetermined degree from their normal path, the fixed contact member being positioned to be operatively associated with the contact elements of the shelves in operative relation to the door opening and being of a length at least equal to the spacing of the shelves so that there is always a contact member of one of the shelves in operative relation thereto.
8. The combination with an endless conveyor, driving means for said conveyor, a series of spaced shelves pivotally mounted on said conveyor, an arm connected to each shelf so that the swinging movement of the shelf is imparted to the arm, connecting links for the arms whereby the swinging movement of one shelf is imparted to all of them, a control means for said driving means including a circuit control element carried by each of said arms and traveling in a predetermined path when the shelves are in normal position, and a pair of coacting relatively fixed circuit control means disposed in opposed spaced relation and on opposite sides of the normal path of the circuit control elements carried by said arms to be contacted thereby when they depart more than a predetermined degree from their normal path.
9. In an oven, the combination of a conveyor, a series of shelves pivotally suspended on said conveyor, a series of laterally projecting pins terminating in contacts at their outer ends adapted to tilt with said shelves, a series of links pivoted at their ends to said pins and connecting them for uniform tilting, a pair of contact strips disposed at opposite sides of the path of said contacts and spaced therefrom to be normally out of contact therewith, the tilting of any one of said shelves acting to tilt all of said levers and bring one of said contacts into contact with one of said strips, and control means including said contacts and strips for shutting down the oven when such contact is established.
10. In an oven, the combination of a conveyor, a series of shelves pivotally suspended on said conveyor, a series of laterally projecting pins terminating in contacts at their outer ends adapted to tilt with said shelves, a pair of contact strips disposed at opposite sides of the path of said contacts and spaced therefrom to be normally out of contact therewith, and control means including said contacts and strips for shutting down the oven when such contact is established.
11. The combination of a conveyor, a series of shelves pivotally supported thereon, a series of depending levers connected to said shelves at their pivots at one end of the conveyor and having laterally projecting pins terminating in contacts at their outer ends, a series of links pivoted at their ends to said pins and connecting said levers for uniform tilting, and control means including said contacts for shutting down the oven when said shelves are tilted a predetermined degree out of their normal path.
12. The combination of a conveyor, a series of shelves pivotally supported thereon, a series of

depending levers connected to said shelves at their pivots at one end of the conveyor and having laterally projecting pins, a series of links pivoted at their ends to said pins and connecting said levers for uniform tilting, and control means for shutting down the oven when said shelves are tilted a predetermined degree out of their normal path.

13. The combination of an endless conveyor having a series of spaced pivotally hung shelves normally maintaining a horizontal position by gravity, depending end levers connected to said shelves at their axes, a series of connecting links pivotally connected at their ends to the outer ends of said levers for keeping said shelves in the same relative horizontal position, and control means for stopping said conveyor when said shelves are tilted more than a predetermined degree from the horizontal.

14. The combination of an endless conveyor having a series of spaced pivotally hung shelves normally maintaining a horizontal position by gravity, a series of connecting links for keeping said shelves in the same relative horizontal position, and control means for stopping said conveyor when said shelves are tilted more than a predetermined degree from the horizontal.

15. The combination of an endless conveyor having a series of spaced pivotally suspended shelves normally maintaining a horizontal position by gravity, connecting means for said shelves whereby they are kept in the same relative horizontal position, and a control means for stopping said conveyor when one of said shelves is tilted more than a predetermined degree from the horizontal.

16. In a baker's oven, the combination with a conveyor having a series of pan shelves and a driving motor, heating means including a gas supply having a valve, and a blower having a driving motor, of automatic control means for stopping said blower and conveyor and closing said gas valve when said shelves tip more than a predetermined degree, said means including arms adapted to tip with said shelves and having lateral contacts, a pair of spaced stationary contact strips arranged at opposite sides of the normal path of said contacts and spaced therefrom to provide therewith a normally open control switch, and control circuit means acting to close said gas valve and stop said blower and conveyor motors on the closing of said control switch and adapted to control the operation of said conveyor motor so that the latter cannot be operated unless the control circuit means is in operative condition.

17. In a baker's oven, the combination with a conveyor having a series of pan shelves, heating means including a gas supply having a valve, and a blower, of automatic control means for stopping said blower and conveyor and closing said gas valve when said shelves tip more than a predetermined degree, said means including arms adapted to tip with said shelves and having lateral contacts, a pair of spaced stationary contact strips arranged at opposite sides of the normal path of said contacts and spaced therefrom to provide therewith a normally open control switch, and control circuit means acting to close said gas valve and stop said blower and conveyor on the closing of said control switch and adapted to control the operation of said conveyor so that the latter cannot be operated unless the control circuit means is in operative condition.

18. In an oven, the combination with a con-

veyor having a series of shelves and a driving motor, heating means including a gas supply having a valve, and a blower having a driving motor, of automatic control means for stopping said blower and conveyor and closing said gas valve when said shelves tip more than a predetermined degree, said means including a control circuit acting to close said gas valve and stop said blower and conveyor motors on the closing of said control switch and adapted to control the operation of said conveyor motor so that the latter cannot be operated unless the control circuit is in operative condition.

19. In an oven, the combination with a conveyor having a series of shelves, heating means including a gas supply having a valve, and a blower, of automatic control means for stopping said blower and conveyor and closing said gas valve when said shelves tip more than a predetermined degree.

20. The combination in an oven, of heating means, an endless conveyor comprising a series of pivotally suspended shelves, driving means for said conveyor, connecting means for said shelves whereby the swinging movement of one shelf on its pivot is imparted to all of them, and a control means for said heating means and driving means comprising a contact member operatively associated with each shelf and normally traveling in a predetermined path but deflected from said path by the movement of its corresponding shelf on its pivot, and a pair of opposed relatively fixed contact members disposed on opposite sides of the normal path of said shelf contact members to be engaged thereby when the shelf contact members are diverted from their normal paths by the swinging of a shelf on its pivot beyond a predetermined degree.

21. The combination in an oven, of heating means, an endless conveyor comprising a series of pivotally suspended shelves, driving means for said conveyor, connecting means for said shelves whereby the swinging movement of one shelf on its pivot is imparted to all of them, and a control means for said heating means and driving means comprising a circuit control member operatively associated with each shelf and normally traveling in a predetermined path but deflected from said path by the movement of its corresponding shelf on its pivot, and a relatively fixed circuit control means disposed at the side of the normal path of said shelf members to be contacted thereby when the shelf members are diverted from their normal paths by the swinging of a shelf on its pivot beyond a predetermined degree, the fixed circuit control means being of such length that there is a shelf member associated therewith and so as to be in operative relation to the member of the shelf in loading position.

22. The combination in an oven, of heating means, an endless conveyor comprising a series of pivotally suspended shelves, driving means for said conveyor, connecting means for said shelves

whereby the swinging movement of one shelf on its pivot is imparted to all of them, and a control means for said heating means and driving means comprising a contact member operatively associated with each shelf and normally traveling in a predetermined path but deflected from said path by the movement of its corresponding shelf on its pivot, and a pair of opposed relatively fixed contact members disposed on opposite sides of the normal path of said shelf contact members to be engaged thereby when the shelf contact members are diverted from their normal paths by the swinging of a shelf on its pivot beyond a predetermined degree.

23. The combination in an oven, of heating means, an endless conveyor comprising a series of pivotally suspended shelves, driving means for said conveyor, connecting means for said shelves whereby the swinging movement of one shelf on its pivot is imparted to all of them, and a control means for said heating means and driving means comprising a circuit control member operatively associated with each shelf and normally traveling in a predetermined path but deflected from said path by the movement of its corresponding shelf on its pivot, and a relatively fixed circuit control means disposed at the side of the normal path of said shelf circuit control members to be contacted thereby when the shelf circuit control members are diverted from their normal paths by the swinging of a shelf on its pivot beyond a predetermined degree.

24. The combination of an endless conveyor comprising a series of pivotally supported shelves, a driving means for said conveyor, connecting means for said shelves whereby the swinging movement of one shelf on its pivot is imparted to all of them, and a control means for said driving means comprising a contact member operatively associated with each shelf and normally traveling in a predetermined path but deflected from said path by the tilting movement of its corresponding shelf on its pivot, and a relatively fixed contact member disposed at the side of the normal path of said shelf contact members to be engaged thereby when the shelf contact members are diverted from their normal paths by the tilting of a shelf on its pivot beyond a predetermined degree.

25. The combination in an oven, of heating means, an endless conveyor comprising a series of pivotally suspended shelves, connecting means for said shelves whereby the swinging movement of one shelf on its pivot is imparted to all of them, and a control means for said heating means comprising a contact member operatively associated with each shelf and normally traveling in a predetermined path but deflected from said path by the tilting movement of its corresponding shelf on its pivot, and a pair of opposed relatively fixed contact members disposed on opposite sides of the normal path of said shelf contact members to be engaged thereby when the shelf contact members are diverted from their normal paths by the tilting of a shelf on its pivot beyond a predetermined degree.

CHARLES T. HATCH.
